TOY EJECTION APPARATUS

Luther L. Lawson, Hawthorne, N. J.

Application September 22, 1950, Serial No. 186,181

1 Claim. (Cl. 124—13)

1

My invention relates to a toy ejection apparatus and more particularly to a toy mechanical means to eject a missile.

In my device I am able to propel a missile and/or aerial toy by mechanical means which is not against the law and which is not dangerous and which does not get out of repair as easily as the present devices.

On form of my invention is illustrated in the accompanying drawing.

Figure 1 is a perspective view of the device. Figure 2 is a longitudinal cross-section.

Figure 3 is a bottom plan view, and

Figure 4 is a similar view of Fig. 2 in a released position.

Reading on Figures 1 to 4 inclusive, my device consists of a barrel member 10, said barrel member having a recessed portion 12 for receiving a handle 11; said barrel member having in its lower portion an inner chamber 13, and a recess 19 to house spring 21. A closing cap 18 fits over the bottom of said chamber, and a release pin 14, projects beyond the bottom of said cap 18 and into said chamber 13, said release pin 14 having a collar portion 15, also contained in said chamber 13; and above said release pin 14 and collar portion 15, is a spring guide stud 16 for spring 21, said pin 14 having a tapered end 17, said closing cap 18 having vent holes 20, said barrel containing in its upper portion a tapered aperture 22 into which tapered aperture 22 fits missile 23, said missile 23 having a tapered portion 25 for fitting into aperture 22, said pin 23 having at its other or upper portion a marker 24.

My device may be operated with or without handle 11. My device operates by striking release pin 14 against a solid object to wit: a cement or flag side walk, earth, stone, wood, metal and/or the like, forcing said release pin 14 into inner chamber 13 of barrel 10, thus causing sufficient air compression so that when the end on release pin 14 hits, or strikes, end 25 of missile 23, the concussion thus created causes the release of said missile 23 to be ejected by the air compressed within said chamber into the atmosphere with considerable force. The contact of said release pin end with the end of said missile acts to release said missile. As soon as the pressure on pin 14 is released the spring 21 will 50 reset the said pin 14 in its original position and the device is then ready to be reloaded. The marker 24 guides and controls the flight of the missile and also serves the purpose of easily locating the discharge missile 23 and making the 55 device and/or toy more attractive and may therefore be painted bright colors so as to be easily visible. The spring 21 merely serves to reset release pin 14 and does not affect the release of the missile 23.

A parachute and/or aerial toy may be used in place of a marker.

2

What I claim is:

A toy ejector comprising, in combination, a barrel member, said barrel member having a slight recess on its outer surface, said recess being capable of receiving a handle, said barrel having an inner chamber extending almost the entire depth of said barrel, said inner barrel chamber having a closing cap on its lower end, said closing cap containing vent holes, said barrel chamber housing a spring, said spring extending the entire depth of said barrel chamber, a release pin projecting through said closing cap into said inner barrel chamber and spring, said release pin having a collar near the end within 10 said inner barrel chamber and beneath said spring, said release pin having a taper on its end passing through said closing cap, said inner barrel chamber containing a spring guide stud extending beyond said collar on said release pin and into 15 said spring, the upper inner portion of said barrel chamber having a tapered aperture, said tapered aperture of said barrel chamber being capable of receiving a missile, said missile also having a slight taper on the end of said missile fitting into 20 said aperture of said barrel chamber, said missile having at its outer end a marker, said tapers of said missile and said barrel chamber being for the easy release of said missile by mechanical means, said means comprising compressed air resulting from said release pin being struck against a solid object forcing the collar on said release pin against said spring and compressing said spring and air in said barrel chamber, and forcing 25 said release pin against the end of said missile, while said spring stud is guiding said spring, and causing said missile to be propelled out of said barrel chamber, and after the release of said missile, said release pin being moved back by said spring until said release pin rests on the bottom of said barrel chamber, said air vents permitting the air beneath the release pin collar to escape as said collar is moved downwardly by 30 said spring, substantially as described.
